COMBINED PAPER TOWEL HOLDER AND RADIO

Josephine R. Louis, Los Angeles, Calif.
(P.O. Box 534, New Town, N. Dak. 58763)

Filed Apr. 26, 1971, Ser. No. 137,732

Term of patent 14 years

Int. Cl. D14—03

U.S. Cl. D56—4

Fig. 1.

Fig. 2.

Fig. 3

FIG. 1 is a perspective view of a combined paper towel holder and radio, showing my new design;

FIG. 2 is a front elevational view; and

FIG. 3 is a side elevational view of the side opposite that shown in FIG. 1.

I claim:

The ornamental design for a combined paper towel holder and radio, substantially as shown.
